[57] CLAIM

The ornamental design for a plaque, as shown and described.

DESCRIPTION

FIG. 1 is a front elevational view of a plaque showing my new design;

FIG. 2 is a left side elevational view thereof;

FIG. 3 is a right side elevational view thereof;

FIG. 4 is a top elevational view thereof; and

FIG. 5 is a bottom elevational view thereof.

The back of the plaque is flat.
